No. 623,422.

Patented Apr. 18, 1899.

G. L. PENZEL & E. MÜLLER.

CLARINET.

(Application filed Oct. 22, 1898.)

(No Model.)

UNITED STATES PATENT OFFICE.

GUSTAV L. PENZEL AND EDWARD MÜLLER, OF NEW YORK, N. Y.

CLARINET.

SPECIFICATION forming part of Letters Patent No. 623,422, dated April 18, 1899.

Application filed October 22, 1898. Serial No. 694,263. (No model.)

To all whom it may concern.

Be it known that we, GUSTAV L. PENZEL and EDWARD MÜLLER, of the city of New York, borough of Manhattan, in the county 5 and State of New York, have invented a new and Improved Clarinet, of which the following is a full, clear, and exact description.

The object of the invention is to provide a new and improved clarinet permitting an 10 easy fingering of the key G-sharp from the keys B-natural and C-sharp without deviating from the usual fingering or compelling the performer to move the little finger of the left hand from the said keys B-natural and 15 C-sharp, the arrangement also permitting an easy trilling of the key G-sharp.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

25 Figure 1 is a front elevation of part of a clarinet provided with the improvement. Fig. 2 is a side elevation of part of the same, and Fig. 3 is an inverted sectional plan view of the same on the line 3 3 in Fig. 1.

30 The improved clarinet is provided with the usual tubular body A, having a key B-natural 1 and a key C-sharp 2, the finger-pieces 3 and 4 of which extend over an arm 5, forming an integral part of the finger-piece 6 for the key 35 G-sharp, as is plainly indicated in the drawings. The finger-piece 6 is fulcrumed on a pivot 8, carried by the body A, and on said pivot is also pivoted the key proper, 7, and said finger-piece is normally held in an outer-

40 most position by a spring 9, a similar but weaker spring 10 pressing on the key 7, with a tendency to hold the latter open. The finger-piece 6 is formed beyond its fulcrum with an arm 11, engaging a lug on said key 7, so 45 that when the said finger-piece 6 is pressed the arm 11 is raised, and thereby permits the spring 10 to force the key 7 to swing outward off its seat, and when the finger-piece 6 is released then the spring 9 returns said finger-piece 6 to an outermost position and also the key 7 to a closed position, owing to the arm

11 engaging the projection or lug on said key. (See Figs. 2 and 3.)

Now it is evident that when the operator presses with the little finger of his left hand 55 on either the finger-piece 3 or 4 to play the keys B-natural and C-sharp, respectively, then said finger-pieces in moving in contact with the arm 5 cause a pressing of the finger-piece 6 and a consequent opening of the key 60 7 to produce G-sharp—that is, to sound the passage—

and when either finger-piece 3 or 4 is released the finger-piece 6 returns to its formal position and closes the key 7, as above described. 70 In other words, my improvement consists of a key (finger-piece) C-sharp or G-sharp connecting with the E or B and F-sharp or C-sharp keys in order that in performing the said passage—

it is only necessary to hold down the B or C-sharp keys and raise the right hand instead of gliding from B or C-sharp keys to G-sharp or C-sharp keys.

Above the free end of the key 7 extends 85 one end of a trilling-lever 12, fulcrumed at 13 on the body A, (see Fig. 2,) and the lower end of said lever is engaged at its under side by an arm 14, carried by the F-sharp ring 15, said lever 12 being normally held with its upper end above the key 7 by a spring 16. (Shown in Fig. 1.)

When it is desired to trill the key G-sharp 7, the operator on pressing the finger-piece 6 and trilling the ring 15 causes the arm 14 to 95 actuate the trilling-lever 12, so that the upper end thereof trills the key 7 as the latter stands in an open position, owing to the pressure of the finger-piece 6 above mentioned.

It is evident that by the arrangement described a performer is enabled to readily play the key G-sharp upon pressing either the key

B-natural or C-sharp without displacing the little finger of the left hand from the finger-pieces 3 and 4. Furthermore, the performer is enabled to readily trill the key of G-sharp 5 from the key F-sharp without displacement of the fingers of the right hand to produce the passage—

Having thus fully described our invention, we claim as new and desire to secure by Letters Patent—

1. In a clarinet, the combination of a G-sharp key consisting of a pivoted finger-piece formed with a rearward extension and a key proper having a connection with said finger-piece whereby it will open when the finger-piece is depressed, but being freely movable independent of the finger-piece when the latter is depressed, a trilling-lever actuated from the key F-sharp and arranged to engage with the key G-sharp proper whereby to trill the same when the finger-piece is depressed, and keys B-natural and C-sharp provided with finger-pieces lying over the rearward extension of the finger-piece of the key G-sharp 30 whereby the key G-sharp may be trilled when either of the said B-natural or C-sharp finger-pieces is depressed, as and for the purpose set forth.

2. A clarinet provided with a G-sharp key 35 consisting of a finger-piece fulcrumed on a pivot on the body of the clarinet and having an arm extending forward of said pivot, and a key proper formed with an arm pivotally mounted on the said pivot independently of the forwardly-extending arm of the finger-piece, the said key-arm being formed with a lateral lug lying under the forwardly-extending arm of said finger-piece, a spring engaging said finger-piece with a tendency to throw 40 the forwardly-extending arm thereof down upon said lug whereby to close the key proper, and a second spring, weaker than the first-named spring and engaging said key proper whereby to throw it open when the forwardly-

extending arm of the finger-piece is raised 50 from the lug, as and for the purpose set forth.

3. A clarinet provided with a G-sharp key consisting of a finger-piece fulcrumed on a pivot and having an arm extending forward of its pivot, a key proper pivoted on the same 55 pivot to move independently of said finger-piece and having a lateral lug lying under the forwardly-extending arm of said finger-piece, a spring engaging said finger-piece, with a tendency to throw the forwardly-extending 60 arm thereof down upon the said lug whereby to close the key proper, a second spring weaker than the first-named spring and engaging said key proper whereby to throw it open when the forwardly-extending arm of the finger-piece 65 is raised, and a trilling-lever having one end lying over the key proper, but normally out of contact with the same, the other end of said trilling-lever being operatively connected with the key F-sharp, as and for the purpose 70 set forth.

4. A clarinet provided with a G-sharp key consisting of a pivoted finger-piece having an arm extending forward of its pivot, a key proper pivoted to move independently of said 75 finger-piece and having a lug lying under the forwardly-extending arm of said finger-piece, a spring engaging said finger-piece with a tendency to throw the forwardly-extending arm thereof down upon the lug to close the 80 key proper, a second spring weaker than the first-named spring and engaging said key proper with a tendency to throw it open, a trilling-lever having one end lying over the key proper, the said lever being actuated from 85 the key F-sharp, and an arm extending from the finger-piece in the rear of its pivot to a point under the finger-pieces of the keys B-natural and C-sharp, and adapted to be engaged by either of said finger-pieces, whereby 90 the key G-sharp may be trilled when either of the said B-natural or C-sharp finger-pieces are depressed, as and for the purpose set forth.

GUSTAV L. PENZEL.
EDWARD MÜLLER.
